LABEL ADJUSTING MEANS FOR LABEL MAGAZINES

Sidney T. Carter, Shrewsbury, Mass., assignor to Geo. J. Meyer Manufacturing Co., Cudahy, Wis., a corporation of Wisconsin

Filed Oct. 16, 1959, Ser. No. 846,975
13 Claims. (Cl. 271—33)

This invention pertains to magazines for labels or similar articles and has for objects the provision of apparatus operative automatically to square up each label in readiness for removal from the magazine; to insure the return of the stack of labels to the bottom of the magazine following the removal of each successive label; and to relieve the lowermost label, preparatory to its removal, from pressure exerted by the overlying stack.

While the invention is herein for convenience described as embodied in a labeling machine, it is contemplated as having other utilities in respect to its broader aspects, more specifically in any situation wherein labels are held in a stack in a magazine holder and picked off one after another by the use of a gum-coated picker.

Commercial labels are not accurate in size, varying within a range of plus or minus $\frac{1}{32}$ of an inch from nominal size. In a given stack of labels, as placed in the label magazine, the variation in size is usually gradual. As the labels are taken one by one from the stack, the operator of the machine must be on the alert to adjust the label-positioning prongs of the magazine at frequent intervals in order that the labels may always be so closely confined that they may not shift so as to become out of square as respects their intended position. In machines in which the endmost label is removed by a gum-coated picker, it is necessary that the stack of labels be capable of movement as a whole in response to the upward pressure exerted by the picker, since in the first place, substantial pressure is necessary to insure a proper coating of the label, and secondly, it would be impractical so to limit motion of the picker that it would make a mere tactical contact with the endmost label. Customarily, the motion of the label stack, in response to the pressure exerted by the picker, is of the order of from $\frac{1}{4}$ to $\frac{5}{16}$ of an inch before the movement of the stack is positively stopped. Although the stack is loaded, as by spring pressure, to urge it downwardly after each respective upward motion, the effective load decreases as the stack diminishes in length. If, in order to prevent the labels from twisting, the operator sets the label-positioning prongs too snugly about the stack of labels, the stack may not return to its initial lowermost position after each picking operation. This is especially troublesome when the magazine comprises compartments for a plurality of labels, from each of which a label is to be taken by a corresponding picker. For example, if one stack of labels is lower down in its magazine than the others, as the pickers approach, the contact of one picker with the lowest stack of labels may prevent the other pickers from applying sufficient pressure to the labels in their respective magazine compartments to insure the proper application of glue, with the result that some of the pickers may fail to withdraw their labels or may drop them after the labels are withdrawn.

It has been found that in the use of labels made of certain types of paper, the downward pressure of the label stack against the lowermost label may result, when attempting to withdraw the label, in the formation of nicks or tears in the lowermost label at the places where the label rests upon the supporting hooks.

The above difficulties are substantially overcome by the employment of the apparatus of the present invention, wherein the label magazine comprises devices defining a compartment within which a stack of freely separable

2

labels may be placed; movable, label-adjusting elements at one side, at least, of said compartment; a picker device operative to withdraw labels one at a time, in succession, from the lower end of the stack; mechanism operative to actuate the picker, cycle-after-cycle; and apparatus operative during each cycle temporarily to urge said label-adjusting elements toward the side of the stack.

Other and further objects and advantages of the invention will be pointed out in the following more detailed description and by reference to the accompanying drawings, wherein,

FIG. 1 is a plan view of a label holder or magazine embodying the novel features of the present invention, showing the label-retaining prongs in horizontal section;

15 FIG. 2 is a fragmentary section, to larger scale than FIG. 1, on the line 2—2 of FIG. 1;

FIG. 3 is a fragmentary side elevation, partly in vertical section, showing the label magazine of the present invention and adjacent parts of the labeling machine;

20 FIG. 4 is a fragmentary section on the line 4—4 of FIG. 2;

FIG. 5 is an edge view, to larger scale, showing one of the label-positioning prongs according to the present invention;

25 FIG. 6 is a side elevation of the prong of FIG. 5;

FIG. 7 is a side elevation of one of the label-adjusting elements;

FIG. 8 is an end elevation of the casing of the motor for actuating the label-adjusting elements; and

30 FIG. 9 is a diagrammatic elevation, partly in vertical section, illustrative of a labeling machine of a general type in which apparatus of the present invention may be embodied.

The magazine, according to the present invention, is 35 useful in and is herein illustrated by way of example as embodied in a labeling machine such as is more fully illustrated and described in the copending application for United States Letters Patent Serial No. 551,012, filed December 5, 1955, by Sidney T. Carter, now issued as Patent No. 2,940,630, dated June 14, 1956, although equally applicable to specifically different types of labeling machines, for instance, that disclosed in United States patent to Carter No. 2,528,944, dated November 4, 1950.

40 As diagrammatically shown in FIG. 9 of the annexed drawings, the machine comprises a main shaft 119 which turns once for each cycle of operation and which, by means of cams, gears, etc. mounted thereon, actuates various parts of the machine, among them an oscillatory picker shaft 187 which is rocked back and forth through a predetermined arc once during each cycle. The machine also comprises a constantly moving conveyor having a horizontal rectilinear run C, upon which articles, for example, bottles, stand as they are moved through the field of action of the label-applying devices. As shown 45 in FIG. 9, the machine is set up to apply labels to but one side of a bottle as the latter moves along the conveyor path but, as disclosed in the aforementioned Patent No. 2,940,630, it may be arranged to apply labels to opposite sides of the bottle. Furthermore, while the machine 50 disclosed in said Patent No. 2,940,630 is arranged to apply a label simultaneously to each of three successive bottles as they are moved along the conveyor path, the apparatus herein shown is, for simplicity of illustration, shown as arranged to apply labels to but two bottles simultaneously, although it is to be understood that the present invention may be embodied in a machine which applies one label at a time or, alternatively, to a machine which applies labels simultaneously to any desired number of articles. As shown in FIG. 9, the frame of the 55 machine carries a fixed bar B extending lengthwise of the machine and which supports the base plate 20 (FIG. 1) of the label holder.

As above noted, the label holder is designed for use in a machine which applies labels simultaneously to two articles, and for this purpose carries two like magazines arranged side by side. Thus the plate 20 has two apertures 21 and 21a, each defining the lower end of a corresponding magazine compartment or cage, and side walls constituted by elongate parallel bars or prongs.

As illustrated in FIG. 3, plate 20 is inclined to the vertical and at such an angle that, as the picker P (which may be of the sliding blade type, such as disclosed in the United States patent to Holm, No. 1,901,101, dated March 14, 1933, or which may be of other customary type), swings upwardly to the label-picking position (FIG. 3), its label contacting face is parallel to the surface of the lowermost label L of the stack S in the magazine compartment. It will be understood that there is a separate picker P corresponding to each magazine compartment, but that all of these pickers are mounted upon the same oscillatory support T carried by the picker shaft 187 and are supplied with gum, in conventional manner, as disclosed for example in the above-mentioned Patents 2,940,630 or 2,528,944. As here illustrated, by way of example, each of the apertures 21 and 21a is approximately rectangular, each having opposite parallel side edges E¹ and E², and rear and front edges E³ and E⁴, respectively.

While, as here illustrated, the apertures 21 and 21a are side-by-side horizontally, it will be understood that, if the magazine is to deliver a body and neck label, for instance for application to a single bottle, one of the apertures will then be to the rear of the other. Associated with each respective aperture is a group of elongate parallel rigid bars or "prongs," the bars or prongs of each group collectively defining a chamber or compartment for the reception of a stack of labels. Since the groups of prongs defining each respective magazine compartment are alike in construction and arrangement, it is necessary herein only to describe in detail one of these groups, for example, that associated with the aperture 21 (FIG. 1).

This group of prongs comprises the prong 23 at the rear edge E³ of the aperture, the prongs 24, 25 and 26 at the front edge E⁴ of the aperture, the prongs 27 and 27a at the edge E¹ of the aperture, and the prongs 28 and 28a at the edge E² of the aperture. It may be noted that the prong 23 and the group of prongs 24, 25, 26 are centrally located with respect to the edges E³ and E⁴, while the prongs of each of the pairs 27, 27a and 28, 28a, are spaced apart and symmetrically located with respect to the front to rear dimension of the aperture, the prong 28 being directly opposite prong 27 and the prong 28a being directly opposite the prong 27a.

Each of the prongs 23, 27, 27a, 28 and 28a and the group comprising the prongs 24, 25, 26 is mounted upon a corresponding individually adjustable carrier such, for example, as the carriers 30 and 31, each of the several carriers being adjustably mounted on the plate 20 so that they may be adjusted to define compartments of different transverse dimensions.

That part of each prong which is secured to the corresponding adjustable carrier is substantially rigid. Desirably the prongs 23, 27 and 28 are shorter, that is to say, their upper ends are at a lower level than the upper ends of the other prongs to facilitate placing a stack of labels in the compartment.

The construction thus far described is substantially conventional in this art.

The lower part of each of the prongs 23, 27 and 27a is, in accordance with the present invention, independent of its normally fixed upper part and movable relatively thereto. Thus, as shown in FIG. 2 for example, the lower portion 270 of prong 27 is pivotally connected at 32 at its upper end to the prong 27 so that the lower end of the part 270 is capable of swinging inwardly toward the label stack. Such inward motion of the lower end of

the part 270 is limited by a pin 33 fixed in the prong 27 and passing loosely through a hole 32a in the part 270. The diameter of this hole 32a is such that the arc of swing of the part 270 is slight. When in normal position as shown in FIG. 2, the inner edge of part 270 is aligned with the inner edge of part 27, the parts being normally held in this relative position by a spring 34 (FIG. 2) whose opposite ends bear respectively against the prong 27 and the part 270. It may be noted (FIGS. 5 and 6) that the prong 27 has a vertically extending slot 27x for the reception of the part 270.

The plate 20 (FIG. 1) is provided with holes 35 for the reception of screws whereby motor devices 36 and 36a are suspended from the plate 20.

15 The motor device 36 comprises a single cylinder within which is arranged a piston (like the piston 38, FIG. 2 which actuates the label-adjusting element associated with or forming a part of the prong 27). A similar motor device 36m (FIG. 1) is associated with the rear prong of the left-hand magazine.

10 The motor device 36a (FIG. 1) has a casing 36x (FIGS. 2 and 8) designed to provide two pairs of cylinders, one pair, for example the cylinders D and D¹ (FIG. 8) receiving pistons 38 which actuate the label-adjusting elements associated with the prongs 27 and 27a respectively of the right-hand magazine. The other pair of cylinders contains pistons for actuating the label-adjusting elements at the right-hand side of the left-hand magazine.

20 The outer end of each piston is slotted to receive a fin 38a at the outer edge of the corresponding label-adjusting element. As shown in FIG. 2, the outer edge of the fin 38a inclines downwardly and outwardly. If the magazine were designed to receive but one stack of labels, 25 the motor 36a would be provided with but a single pair of cylinders.

The several cylinders are supplied with pressure fluid, for example, compressed air, by means of a manifold M (FIG. 1) which receives the pressure fluid from a

30 suitable source through a pipe 39 (FIG. 1), the supply of fluid being controlled by a three-way solenoid valve 40 (FIG. 9), which is actuated by a limit switch 41 having an arm 42 contacting a cam 43 on the main shaft 119. The cam is so contoured that as the picker enters the

35 magazine compartment and lifts the label stack from the hooks H, air is admitted to each motor cylinder, thereby swinging the lower ends of the several label-adjusting elements 270 inwardly so that the inner edges of these elements are inclined inwardly and downwardly relative to the chamber wall. When the picker completes its upward motion and starts to retreat from the magazine, carrying with it the lowermost label from the stack, the parts 270 still remain in the position to which they were moved by the motor, thus retaining the stack in the elevated position until the cam 43 has turned through a predetermined angle, for example as illustrated in FIG. 3, through an angle of 212°, whereupon the air is exhausted from the cylinders and the label-adjusting elements 270 are returned to their normal position by the springs 34,

40 thus allowing the label stack to drop until the lower label of the stack rests upon the upper surfaces of the hook members H (FIG. 7) at the lower ends of some at least of the prongs, these hooks being conventional and of sufficient dimensions to prevent the smallest label comprised in the stack from dropping out through the aperture 21. However, while the stack is raised and supported by the inwardly inclined member 270, the free margin of the single label adhering to the downwardly moving picker flexes readily so as to pass the hooks H without tearing.

45 At each successive cycle, the labeling adjusting elements 270 function as above described, and thus gradually square up the labels in the lower part of the stack so that even though some of the labels be of a size such that they may move transversely within the label compartment, the 50 repeated operation of the label-adjusting elements is such

as to urge all of the labels transversely into contact with the fixed prongs 28 and 28a and the group of fixed prongs 24, 25 and 26 at the opposite sides of the label compartment from the several label-adjusting elements. In actual practice it has been found that the labels constituting at least the lower half inch of the stack are always accurately squared with reference to the fixed prongs.

While label-adjusting elements have here been shown as located at two adjacent sides of the label magazine, it is contemplated that it may be sufficient, under certain conditions, to provide such a device or devices at but one side of the magazine.

As here illustrated (FIG. 3), the magazine is provided with the usual devices for applying pressure to the top of the label stack, including a plate 50 which rests upon the uppermost label in the stack, this plate being fixed to the lower end of a rod 51 which is capable of sliding in a guideway provided in the fixed supporting member 52 carried by the machine frame. A spring 53 embracing the upper part of the rod 52 and whose lower end rests upon a collar 54 fixed to the rod and whose upper end engages a so-called "lip" 55, normally urges the plate against the label stack. The lip 55 is provided with an angular portion 56 having an aperture through which passes a fixed square rod 57. When a fresh stack of labels is placed in the magazine, the lip 55 is adjusted upon the rod 57 so as to provide a positive stop to limit upward motion of the rod. The lip 55 will not move along the rod 57 so long as upward pressure is exerted against it, but is manually adjusted so as to permit the rod 51 to move upwardly through a distance of from $\frac{1}{4}$ to $\frac{5}{16}$ of an inch in response to the upward pressure exerted by the picker against the lowermost label in the stack, the spring 53 normally returning the stack to its lowermost position when the picker retreats. However, as the stack becomes shorter, the upper end of the rod 51 will move away from the lip 55, although the spring 53 will continue to press upwardly against the latter and so prevent the latter from moving down on the rod 57. However, when the stack becomes so short that the spring 53 exerts but little downward force, and if the prongs have been adjusted too closely, the stack may fail to move down to its lowermost position when the picker retreats.

By the present arrangement, in which provision is made for automatically adjusting the labels during the operation, it is not necessary to set the prongs so closely as is often done and thus the danger of the jamming of the stack in its uppermost position is minimized. On the other hand, by temporarily holding the stack in its uppermost position by the action of the elements 270 during the picking operation, the lowermost label is freed from the downward pressure normally exerted by the follower plate 50 so that danger of tearing the label, as it is withdrawn by the picker, is avoided.

While one desirable embodiment of the invention has herein been described by way of example, it is to be understood that all modifications of the disclosed apparatus which fall within the terms of the annexed claims are to be regarded as within the purview of the invention.

I claim:

1. In combination in a machine which includes a freely separable label magazine having a chamber within which a stack of freely separable labels may be placed, normally fixed prongs defining one wall, at least, of said chamber and a gum-coated picker operative to withdraw labels, one at a time successively, from the lower end of a stack of labels within said chamber, and power-actuated means operative, after each successive label is withdrawn, automatically to shift the labels, constituting the lower part, at least, of the stack, edgewise toward and into contact with said fixed wall thereby to square up the relatively movable labels in the lower part of the magazine.

2. In combination, in a labeling machine which comprises a label magazine having a chamber within which a stack of freely separable labels may be placed, normally

fixed parts defining two adjacent walls of said chamber, at least one movable label-adjusting part being arranged at the opposite side of the chamber from each of said fixed walls, respectively, each of said label-adjusting parts comprising a smooth label-engaging edge normally extending substantially parallel to the height of the stack and so located as to contact the edges of those labels which constitute the lower portion only of the stack, and power-actuated devices operative so to actuate said label-adjusting parts as to shift edgewise any labels, within the lower portion of the stack, which have become misplaced thereby to square them up by contact with the fixed walls of the magazine.

3. In combination, in a labeling machine which comprises a label magazine including elements operative to define a chamber within which a stack of freely separable labels may be placed, stack-supporting hooks upon which the lowermost label of the stack normally rests, a pivotally suspended support for each hook, each support having an elongate label-contacting, smooth inner edge above the hook, said edge normally extending substantially parallel to the height of the stack, means yieldably urging the stack downwardly toward said supporting hooks, a gum-coated picker, means operative to move the picker into contact with the lowermost label in said chamber and, by upward pressure thereagainst, to elevate the entire stack within the chamber, and means operative to swing said pivoted hook-supports inwardly, as the stack rises and temporarily to retain them in the latter position whereby, by contact of the smooth inner edges of the hook-supports with the edges of those labels which constitute the lower part of the stack, to retain the stack in elevated position while the picker is retreating from the magazine and withdrawing the lowermost label from the stack, the downwardly and inwardly inclined smooth edges of the hook-supports acting as cams, as the picker retreats from the chamber, to urge the labels within the lower part of the stack edgewise toward the opposite wall of the chamber.

4. In combination, a label magazine comprising normally stationary bars defining the sides of a chamber within which a stack of freely separable labels may be placed, supports upon which the lower labels of the stack, so placed, may rest, a gum-coated picker operative to enter the chamber and lift the stack and then to retract and withdraw a label from the lower end of the stack, mechanism operative to actuate the picker, cycle after cycle, movable label-adjusting elements located at the lower ends of those chamber-defining bars which are at one side of said chamber, and power-actuated means operative, during each successive label-picking phase of said cycle, so to dispose said adjusting elements that as the stack descends, following the retreating picker, the labels at the lower portion only of the stack are urged toward those bars which are at the opposite side of the chamber.

5. A label magazine for use in a machine which comprises a cam-actuated, gum-coated picker operative to remove labels one at a time from the bottom of a stack of freely separable labels, said magazine comprising substantially parallel, normally stationary bars collectively defining the side walls of a chamber for the reception of a stack of labels, a label-adjusting element extending downwardly from the lower end of each of said bars which are located at one side, at least, of said chamber, said adjusting elements having label-contacting edges and being capable of movement from a normal position, wherein said edges are parallel to the side wall of the chamber, inwardly with respect to said chamber, to a position wherein their label-contacting edges incline inwardly and downwardly, and power-actuated means operative so to position said label-adjusting elements that said edges are inclined inwardly and downwardly during the withdrawal of the lowermost label from the stack by the picker.

6. A label magazine for use in a machine which comprises a cam-actuated, gum-coated picker operative to remove labels one at a time from the bottom of a stack of freely separable labels, said magazine comprising substantially parallel, normally stationary, but relatively adjustable bars collectively defining the side walls of a chamber for the reception of a stack of freely separable labels, a label-adjusting element pivotally attached to the lower end of each of those bars which are located at two adjacent sides respectively, of the chamber, each of said elements having a label-contacting edge which is normally aligned with the inner edge of the bar with which it is associated, and power-actuated means, acting in timed relation to the motion of the picker, operative to move each adjusting element inwardly, just prior to the withdrawal of a label by the picker, to a position in which its label-contacting edge is inclined downwardly and toward the opposite wall of the chamber, whereby, as the picker retreats from the chamber, the labels at the lower part of the stack, by engagement with said inclined edges, are urged toward the opposite wall of the chamber.

7. A label magazine for use in a machine which comprises a gum-coated picker operative to remove labels one at a time from the bottom of a stack of freely separable labels, said magazine comprising substantially parallel, normally stationary bars having substantially rectilinear edges which collectively define the side walls of a chamber for the reception of a stack of labels, at least one bar, at each of two adjacent sides of the chamber, having an elongate slot at its lower end, a movable label-adjusting element having a rectilinear inner edge and a stack-supporting hook at its lower end and having its upper end disposed within the slot of each of said slotted bars, pivot means uniting each adjusting element to the corresponding bar, means normally holding each of said adjusting elements positioned with its inner edge aligned with that bar with which it is associated, and motor devices automatically operative to move said label-adjusting elements toward the opposite sides, respectively, of said chamber during each label-picking phase of the cycle of operation of the machine.

8. In combination with a label magazine for use in a machine which comprises a cam-actuated, gum-coated picker operative to enter the magazine, lift a stack of freely separable labels disposed within the magazine and retreat from the magazine, taking with it the lowermost label, parts forming the side walls of the magazine chamber, at least two movable label-adjusting elements at the lower portion of one side of said chamber, each having a label-contacting edge and a stack-supporting hook at its lower end, a spring urging each label-adjusting element outwardly, stop means so limiting such outward movement that the label-contacting edge of each adjusting element is normally flush with the inner surface of the chamber wall, and power-actuated means operative simultaneously to move said elements, just prior to the retreat of the picker from the magazine, to a position wherein their label-contacting edges incline downwardly and toward the opposite wall of the chamber, whereby, as the stack descends, following the retreating picker, said inner edges of the adjusting element, by contact with the edges of misplaced individual labels at the lower part of the stack, square up said labels with the opposite wall of the chamber.

9. In combination, in a labeling machine, a label magazine comprising substantially parallel, normally stationary, spaced elongate rigid bars having rectilinear inner edges which collectively define the side walls of a chamber for the reception of a stack of freely separable labels, an elongate rigid member pivotally attached, at its upper end, to the lower end of each of certain, at least, of said bars, each of said members having a substantially rectilinear label-contacting inner edge and having an inwardly directed stack-supporting hook at its lower end, spring

means tending to swing each of said hooked members outwardly, and stop means so arranged as to limit such outward movement so that the inner edge of each of said hooked members is normally aligned with the inner surface of a side wall of the chamber with their hooks in stack-supporting position, a gum-coated picker for withdrawing labels from the magazine, means for advancing the picker into the magazine chamber so as, by contact with the lowermost label of the stack, to lift the entire stack from the supporting hooks, power-actuated means operative to swing the hooked members inwardly as the stack rises so that their label-contacting edges incline inwardly and downwardly and temporarily to hold them so as to maintain the stack in elevated position by engagement of the stack with the inner edges of said hooked members as the picker retreats, carrying the lowermost label with it, the margins of said lowermost label being free from constraint, during retreat of the picker, so that they pass said hooks without being torn, said power-actuated means being operative, as the picker retreats, to permit the hooked members to swing outwardly to normal position so that the stack drops onto said hooks.

10. In combination, a label magazine comprising a supporting plate having a substantially rectangular aperture which defines the lower end of a rectangular chamber for the reception of a stack of freely separable, rectangular labels, and means operative alternately to lift the stack and permit it to drop, a plurality of substantially parallel, normally stationary, spaced rigid bars collectively defining the side walls of said chamber, each of two side walls, at least, of the chamber being constituted by a pair of said bars, each bar of one of said pairs having extending downwardly from its lower end an elongate label-adjusting element whose upper end is pivotally connected to the bar with which it is associated, a spring and a limiting stop whereby each adjusting element is normally positioned with its inner edge aligned with that of the corresponding bar, each adjusting element being capable of swinging inwardly toward the label stack until its label-contacting edge is inclined inwardly and downwardly, and power-actuated means operative simultaneously to swing both label-adjusting elements toward the bars of the opposite pair respectively, just before the label stack is permitted to drop, whereby contact of the edges of displaced labels in the lower part of the stack with the inclined edges of said adjusting elements causes the labels to shift transversely until they are square with the edges of the aperture in the supporting plate.

11. A label magazine according to claim 4, wherein the means for moving said label-adjusting elements are fluid pressure motors, each corresponding to one respective adjusting element, each motor having a piston which engages the outer edge of the corresponding adjusting element, and automatically acting means for supplying pressure fluid to each of said motors.

12. A magazine according to claim 10, for use in a machine which includes a gum-coated picker and mechanism for actuating the picker once for each label-applying cycle and wherein the supporting plate has a plurality of substantially rectangular apertures, each, respectively, defining the lower end of a rectangular chamber for a stack of freely separable labels and wherein two opposite sides of each respective chamber are constituted by a pair of said bars, each bar of one of said pairs having extending downwardly from its lower end a movable label-adjusting element, and wherein a fluid pressure motor is provided for moving each of said label-adjusting elements from an inoperative to an operative position, and means for supplying pressure fluid simultaneously to each of the several motors during each machine cycle.

13. A multiple-compartment label magazine for use in a machine which comprises a shaft which turns once for each machine cycle, gum-coated pickers operative simultaneously to enter the respective magazine compartments

and to lift label stacks disposed within the label-receiving compartments of the magazine and then to retreat, carrying labels with them, said magazine comprising a supporting plate having a plurality of apertures therein, each defining the lower end of the corresponding compartment, at least one side wall of each respective compartment being defined by the parallel rectilinear inner edges of normally stationary bars, a movable label-adjusting element extending downwardly from the lower end of each of said bars, each adjusting element having a label-engaging edge, yieldable means which normally positions each adjusting element so that its label-engaging edge is aligned with the inner edge of the corresponding bar, motor means operative to move each such label-adjusting element inwardly to a position wherein the label-adjusting edge of said element is inclined inwardly and downwardly toward the opposite wall, motor control means, including a cam on said shaft, operative to cause the motor means to move said adjusting elements inwardly as the pickers,

in entering the magazine compartment, lift the respective stacks of labels, said control means being operative to keep the motor means energized and thereby hold the label stacks in elevated position until the pickers start to retreat, carrying labels with them, and then to de-energize the motor means thereby to permit the several label-adjusting elements to move out relatively to the chamber so that the edges of the lowermost labels may slide downwardly in contact with the inner edges of said adjusting elements as the respective label stacks drop.
